UNITED STATES PATENT OFFICE

H MILLER ANDERSON, OF CHICAGO, ILLINOIS, ASSIGNOR, BY MESNE ASSIGNMENTS,
TO THE LAKE ERIE CHEMICAL COMPANY, OF CLEVELAND, OHIO, A CORPORATION
OF OHIO

GAS-DISCHARGING DEVICE FOR SAFES

Application filed November 7, 1928. Serial No. 317,811.

The object of this invention is to provide a simple, inexpensive, and easily applied mechanism for effecting the discharge of a poison gas upon a burglar's attempted entry 5 into an enclosure such as a vault or safe.

Numerous other objects and advantages of the invention will be apparent as it is better understood from the following description, which, taken in connection with the accompanying drawings, discloses a preferred embodiment thereof.

In the drawings:

Figure 1 is a perspective view of an improved gas discharging mechanism constructed in accordance with the invention;

Fig. 2 is a front elevational view of the same;

Fig. 3 is a vertical section, partly in elevation, showing the parts of the poison gas 20 bomb firing mechanism; and

Fig. 4 is a top plan view, partly in section, of the supporting bracket for the firing mechanism and the gas bomb.

One of the usual modes of application of 25 the invention is to a vault door, a fragment of which is shown at 11 in Fig. 3. The vault door 11 is provided with the usual combination lock contained within the box or casing 12, mounted on the inner surface of the door 30 and controlling the operation of the usual bolt work, not shown, which is advanced into suitable keepers in the door frame to lock the vault and retracted to release the vault door for opening movement.

35 A common mode of procedure on the part of a burglar attempting to force an entry into a vault is to punch or blow in, or otherwise dislocate the combination box from the vault door. The illustrative gas discharging mechanism is shown as controlled in its operation by such dislocation of the combination box.

The various parts of the gas bomb discharging mechanism are supported by a bracket 13 45 comprising a vertically arranged plate member 14 provided with holes 15 whereby it may be secured to the inner surface of the vault door 11. The upper end of the bracket plate 14 is provided with an inwardly extending overhanging shelf or support 16, and the low-

er end of said plate 14 with a pair of inwardly extending horizontal supporting lugs 17.

Secured to the plate 14 and projecting inwardly therefrom are superposed supporting rods 18 and 19. The upper supporting rod 18 is made somewhat shorter in length than the lower rod 19, as shown in Figs. 1 and 3. These supporting rods 18 and 19 are respectively provided with aligned vertical holes 20 and 21 constituting bearings for the passage of a vertical firing pin 22. The upper end of the firing pin 22 extends approximately to the lower surface of the shelf 16 and said pin is formed with a channel or socket 23 extending part way down from its top. The channel or socket 23 receives a coil spring 24, the upper end of which engages the lower surface of the shelf 16 and the lower end the bottom 25 of the socket 23. When the firing pin is released, the spring 24, which is maintained normally under compression, will cause the firing pin to drop with a sharp blow and hit the cap or firing plunger of a poison gas bomb.

The firing pin 22 is released for operation by a trigger mechanism, as follows:

As shown in Fig. 3, the pin 22 is provided with an annular horizontal groove 26 located in that portion of the pin which is normally disposed within the bearing hole 20 in the upper supporting rod 18. A trigger pin 27 projects through a hole in the free end of the rod 18, in registry with the groove 26, and enters said groove normally to hold the firing pin in its elevated inoperative position. The trigger pin 27 is secured at 28 in any suitable manner to the trigger operating bar 29. This bar 29 is provided with a yoke 30 at its lower end which embraces the squared end portion 31 of the rod 19. From the opposite wings of said yoke, ears 32 project parallel with the sides of said portion 31 and are pivoted thereto in any suitable manner, as shown at 33. This construction permits a pivotal swinging movement of the trigger operating bar 29.

The trigger operating bar 29 is bent at 34 into the horizontal portion 35, which overlies the shelf 16, and thence is rebent at 36 into the upstanding end 37. This end 37 is made

ong enough to extend upwardly beyond the ottom of the combination box 12 and is se-
ured by any suitable means, such as a screw
8 to the rear face of the combination box.
A leaf spring 39 bears against the trigger
operating bar 29 and exerts pressure thereon
so as to thrust said bar outwardly. This leaf
spring 39 is secured at its opposite ends 40
by screws 41 fast to the horizontal shelf 16.
With the above described construction, dis-
location of the combination box from any
cause, will impart a pivotal swinging move-
ment, assisted by the spring 39, to the trigger
operating bar 29, in a direction away from
the end of the rod 18. Such movement about
the axis 33 will withdraw the trigger pin 27
from the groove 26 in the firing pin 22 and
permit the spring 24 to operate the firing pin
in the manner hereinbefore described. The
leaf spring 39 is made strong enough to in-
sure a quick, positive operating movement
of the bar 29 whenever the combination box
is dislocated.

As shown in Fig. 3, the groove 26 in the
firing pin 22 may be made relatively shallow.
Hence, very little movement is required to
disengage the trigger pin 27 from the firing
pin 22, and the action is therefore instantane-
ous.

The gas bomb for discharging the poison
gas into the vault or other enclosure is
mounted in such position that the cap or
other bomb operating device receives the im-
pact of the firing pin 22. As shown in Fig-
ures 1 and 3, the firing pin 22 is provided at
its lower end with a point 42 for striking
the cap or other operating device of the gas
bomb to discharge the same. The gas bomb
is indicated by dotted lines at 43 in Fig. 1,
and is provided with a cap or other firing de-
vice 44. A supporting bracket 45 is provided
for positioning the gas bomb 43 beneath the
firing pin 22. This bracket 45 consists of a
vertical bar 46 having its lower end bent in-
wardly to provide a short flange 47 which ex-
tends below the bottom edge of the plate 14
between the horizontal lugs 17. The upper
end of the vertical plate 46 is provided with
a hole 48 by which the upper end is hung
on a pin 49 projecting inwardly from the
bracket plate 14. There is also provided at
the upper end of said supporting bracket 45
a collar 50 which embraces and supports the
flanged top of the bomb 43. This construc-
tion provides a simple and effective support
for the removable bomb 43.

If desired, the bomb 43 may be protected
by a casing 51 supported at its lower end on
the lugs 17 and extending upwardly to the
shelf 16, as shown in Fig. 2. The casing,
however, will permit the escape of the nox-
ious fumes of the poison gas on the discharge
of the bomb 43 and for this purpose is pro-
vided with an opening 52. A pin 53, in-
sertable in a lateral hole 54 in the pin 49, may

be employed to prevent displacement of the
bracket 45. This pin 53 is curved so as to be
easily manipulated. If desired, the pin 53
may be also utilized for the purpose of lock-
ing the firing pin 22 against movement. In
this case, the rod 18 is provided with a hole
55 located in one of its sides and in registry
with the groove 26 in the firing pin 22. By
inserting the pin 53 through the hole 55, the
pin may be projected into the groove to hold
the firing pin 22 locked against operative
downward movement.

It is thought that this invention and many
of its attendant advantages will be under-
stood from the foregoing description, and it
will be apparent that various changes may
be made in the form, construction and ar-
rangement of the parts, without departing
from the spirit and scope of the invention,
or sacrificing all of its material advantages,
the form hereinbefore described being mere-
ly a preferred embodiment thereof.

I claim:

1. The combination with a vault combina-
tion box, of a supporting bracket mounted
adjacent thereto, a poison gas bomb carried
by said supporting bracket, a firing mecha-
nism for said bomb also carried by said sup-
porting bracket, said firing mechanism com-
prising, a pair of pin guiding rod mem-
bers, a firing pin guided thereby, said firing
pin being provided with an annular groove
disposed within one of said rod members, a
trigger entering the head of said rod member
and engaging said firing pin within said
groove, a spring adapted when released to
project said firing pin into bomb discharg-
ing engagement with said bomb, a trigger op-
erating bar pivoted to the other of said pin
guiding members and engaging said trigger,
said trigger operating bar being secured to
said combination box, whereby to release said
trigger on dislocation of said combination
box.

2. The combination with a vault combina-
tion box, of a supporting bracket mounted
adjacent thereto, a poison gas bomb carried
by said supporting bracket, a firing mecha-
nism for said bomb also carried by said sup-
porting bracket, said firing mechanism com-
prising, pin guiding rod members, a spring
operated firing pin guided thereby, a trigger
engaging said firing pin for holding the same
normally inoperative, a trigger operating
member for releasing said trigger on dislo-
cation of said combination box, and a spring
for throwing said trigger operating member
to trigger releasing position on release there-
of by said combination box.

3. The combination with a vault combina-
tion box, of a supporting bracket mounted
adjacent thereto, a poison gas bomb carried
by said supporting bracket, a firing mecha-
nism for said bomb also carried by said sup-
porting bracket, said firing mechanism

comprising, a pair of pin guiding rod members, a firing pin guided thereby, said firing pin being provided with an annular groove disposed within one of said rod members, a trigger entering the head of said rod member and engaging said firing pin within said groove, a spring adapted when released to project said firing pin to bomb discharging engagement with said bomb, a trigger operating bar pivoted to the other of said pin guiding members and engaging said trigger, said trigger operating bar being secured to said combination box, whereby to release said trigger on dislocation of said combination box, and a spring for throwing said trigger operating bar to trigger releasing position on release of said bar by said combination box.
